(57) **CLAIM**

We claim the ornamental design for a combined battery and charger assembly, as shown and described.

DESCRIPTION

FIG. 1 is a perspective view of a combined battery and charger assembly according to the claimed design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

In the drawings, the broken lines are for the purpose of showing portions of the combined battery and charger assembly that forms no part of the claimed design.
